UNITED STATES PATENT OFFICE.

GUSTAVE M. MINTON, JR., OF NEW YORK, N. Y.

SERVING TRAY.

Application filed February 25, 1927. Serial No. 171,015.

The object of the present invention is to provide a metal serving tray which shall be collapsible and which shall comprise two or more tray units so supported by a frame that the latter acts, in addition to its supporting function, as a latching means for holding the tray units in their various positions.

The invention will be understood by reference to the accompanying drawings, in which—

Figure 1 is a plan view of an embodiment of the invention showing the tray units placed in the same horizontal plane, and

Figure 2 is a perspective view of the same with the tray units in position for use;

Figure 3 is a sectional detail on the line 3—3, Figure 1;

Figure 4 is a detail view, partly in section, showing a modification in the latching means for the tray units, and

Figure 5 is a side elevation of the same;

Figure 6 is a detail perspective view of a corner of the modified tray structure, showing the passage for the pivot pin, and

Figure 7 is a perspective view of one end of the frame member showing the manner in which the pivot pin is held;

Figure 8 is a detail view on the line 8—8, Figure 5, and partly in section.

In both embodiments of the present invention the frame consists of two spring end members 1 which are connected by a bar 2. The end members 1 pivotally support two trays 3 and 4.

In the embodiment illustrated in Figures 1 and 2 each tray carries at opposed points cup-like projections 5 which are shown in cross section at Figure 3. The cup-like projections 5 fit into socket members 6 carried at the ends of frame members 1. Each socket member 6 is formed with one or more sets of opposed recesses 7 of a size adapted to receive the turned edge 4* of a tray unit. The distance between the wall of recess 7 of one socket member 6 and that of the corresponding opposite socket member carried by the coacting frame member will be less than the length of the tray pivotally supported in such socket members, so that when the parts

are assembled members 1 will be slightly sprung back at their ends so as to exert a gripping pressure upon the tray units. When the tray units are moved to the position shown in Figure 2, the turned edges 4* of each tray will fit into their appropriate recesses in the socket members 6 and the

walls of the recesses will act as latches for the tray units, with an action sufficient to hold the units against undue movement when light objects are placed upon them, but insufficient to prevent collapse of the tray by manual movements.

In practice it is desirable that the lower tray be of greater area than the upper tray and I have shown such construction in the drawings.

In Figures 4 to 8 inclusive I have illustrated a modification of the tray shown in the preceding figures, pivot pins being employed intermediate the frame members 1 and the tray units. The two rolled side edges of each tray unit are formed with apertures 8, each aperture being adapted to receive a pin 9 carried at one end of a spring frame member 1. Said members 1 do not carry socket members 6 as in the construction shown in Figures 1 and 2 but they are depressed at 10, Figure 7, to form latching recesses for the rolled side edges of the tray units. The pins 9 are headed and are located in the centres of depressions 10. A feature of the construction is that the heads of the pins 9 are covered by laminating the spring frame members 1, and the laminations may be formed by folding a plate upon itself and thence angularly in the shape indicated in full in sectional lines, Figure 4, the laminations of the ends of the structure then being bent away from each other for the insertion of pins 9, whereupon the ends may be brought back into close contact as indicated in the drawings.

The walls of the recesses 10, in the said modification, serve the same function as the recesses 7 in the construction shown in Figures 1 and 2. The ends of the frame members 1 will be sprung outwardly when the tray units are assembled on the frame and therefore when the rolled edges of the tray units are positioned within recesses 10 there will be a frictional pressure thereupon by members 1, resisting displacement of the units from the recesses, which resistance will be sufficient to enable each tray to support light objects.

Having described my invention what I claim and desire to secure by Letters Patent is as follows:

1. A serving tray comprising a plurality of spring side frame members connected together and a plurality of tray units, each tray unit being pivotally supported by two

opposed spring frame members, a rigid member connecting said frame members intermediate their ends in combination with means whereby a predetermined movement 5 of a tray unit relatively to said frame members springs the latter slightly apart until said members are permitted to move inwardly into latching relationship with said unit.

2. A serving tray comprising two opposed 10 spring frame members, a rigid bar connecting said members whilst leaving their ends free for spring action, a tray unit pivotally supported by one frame member at one end thereof and by the second frame member at 15 its corresponding end, a second tray unit pivotally supported between and by the remaining frame member ends, said frame member ends being provided with recesses,

the walls of which are adapted to engage edges of the trays when the latter are moved 20 to given positions, the arrangement being such that when the trays are moved from said positions the frame members are sprung in a direction away from the tray units.

3. A serving tray comprising opposed 25 spring frame members, a rigid bar connecting said members intermediate their ends, recesses formed in the ends of said members, the walls of which are adapted to embrace the edges of the trays, and pins adjacent 30 said recesses and held by the frame members, said pins entering apertures formed in the edges of the tray units.

In testimony whereof, I have signed my name to this specification.

GUSTAVE M. MINTON, JR.
